US00D625463S

(12) **United States Design Patent**
Klus

(10) **Patent No.:** **US D625,463 S**
(45) **Date of Patent:** **** Oct. 12, 2010**

(54) **LED-BASED LINEAR LIGHTING APPARATUS
WITH ROUNDED HOUSING**

(76) Inventor: **Sylwester Klus**, Swierkowa 6, 05-502, Kamionka (PL) 3

(**) Term: **14 Years**

(21) Appl. No.: **29/354,012**

(22) Filed: **Jan. 18, 2010**

(51) **LOC (9) Cl.** 26-99

(52) **U.S. Cl.** D26/138

(58) **Field of Classification Search** D13/179, D13/180; D16/101, 135; D25/122, 124; D26/9, 11, 22, 25, 56, 67, 71, 72, 74, 76, D26/79, 84, 85, 88, 89, 113, 118, 119, 120, D26/121, 122, 123, 124, 128, 129, 130, 134, D26/137, 138, 139, 140, 141, 142, 152; 52/844; 359/811, 819; 362/145, 152, 219, 240, 241, 362/249.01, 249.02, 249.03, 249.04, 249.05, 362/249.06, 249.07, 249.08, 249.09, 249.1, 362/547, 555

(57) **CLAIM**

The ornamental design for the LED-based linear lighting apparatus with rounded housing, as shown and described.

DESCRIPTION

FIG. 1 is a top perspective view of the LED-based linear lighting apparatus with rounded housing showing the new design;

FIG. 2 is a bottom perspective view thereof;

FIG. 3 is a front view thereof;

FIG. 4 is a side view thereof;

FIG. 5 is a top view thereof; and,

FIG. 6 is a bottom view thereof.
